UNITED STATES PATENT OFFICE.

GEORGE M. COCKE, OF MILWAUKEE, WISCONSIN, ASSIGNOR TO THE FULLER-WARREN COMPANY, OF WISCONSIN.

DESIGN FOR A HEATING-STOVE.

SPECIFICATION forming part of Design No. 26,249, dated November 3, 1896.

Application filed July 27, 1894. Serial No. 518,768. Term of patent 7 years.

To all whom it may concern:

Be it known that I, GEORGE M. COCKE, of Milwaukee, in the county of Milwaukee and State of Wisconsin, have invented and produced a new and original Design for Stoves; and I do hereby declare that the following is a full, clear, and exact description of the invention, which will enable others skilled in the art to which it pertains to make and use the same, reference being had to the accompanying photograph, and to the letters of reference marked thereon, which forms a part of this specification.

The accompanying photograph represents in perspective a parlor-heater illustrating my design.

The main parts of the stove are designated by letters and the details of ornamentation by figures.

The leading features of the design consist of a low dome-shaped cover A, approximately square in horizontal section, having rounded corners, a plain beveled rim or band 1 at the base, and vine and leaf-like open-work ornamentation 2; an urn B, surmounting the cover, having a vertically-beaded surface, plain horizontal bands, arabesque wings or handles 3 3 on opposite sides, and an arabesque finial 4 at the apex; a top section C, approximately square in horizontal section, having protuberant rounded corners, a plain beveled rim or band 5 at the base, an ovolo molding 6 with circular convex ornaments at intervals at the inner upper edge around the base of the cover A, and open-work scroll and leaf-like ornamentation 7 between the rim 5 and molding 6, the general surface of said section C being curved upwardly and inwardly from the rim 5 to the molding 6; the upper body-section D, approximately square in horizontal section, having a frieze or outwardly-projecting ornamented band 8 with protuberant rounded corners, quinquefoliate ornaments 9 at the corners, circular convex or shield-shaped ornaments 10 at the center of each side and intermediate leaf and scroll ornamentation in low relief, vertically-fluted tapering columns 11 11 at each corner, arch-shaped panels 12

with open-work leaf and scroll ornamentation in the sides, an arched door d in the front 50 panel with S-shaped leaf and scroll ornaments 13 13, placed side by side and turned in opposite directions, and an intermediate round convex figure 14, and concentric curved studded bands 15 15 and an arch-shaped band 55 16, consisting of two curved bars approximately parallel with the top of the door with intermediate open scrollwork; a lower body-section E, similar in general shape and contour to the upper section D, but not so high, 60 separated from said upper section by a horizontal band 17, studded at intervals with circular convex figures and intermediate leaf-like ornamentation and having tapering fluted columns 18 18 at the corners, and open-work 65 panels with X-shaped open scroll ornaments 19, volute ornaments 20 in the corners, and leaf-like ornaments 21 21; an ogee-shaped base F, having scroll and leaf-like surface ornamentation in low relief, rounded corners, and 70 a door f with a T-shaped scroll and leaf ornament 22; a name-plate 23 between the lower body-section E and base F, having a grained or wavy-line surface and leaf-like ornaments 24 24 at the ends; foot-rests G G on 75 each side of the base, having beveled ends with trifoliate ornaments 25 25, and an ornamental base-skirting H, approximately square in horizontal section and curved outwardly and downwardly from the base and 80 having rounded corners, legs h h, with pendant leaf-like ornaments 26, springing from the upper margin of the skirting, and bifoliate ornaments 27 on the feet, and intermediate scroll and leaf-like surface ornamentation in 85 low relief.

I claim—

The design for a stove, as shown and described.

In testimony that I claim the foregoing as 90 my own I affix my signature in presence of two witnesses.

GEO. M. COCKE.
